UNITED STATES PATENT OFFICE.

DAVID M. WESTON, OF BOSTON, MASSACHUSETTS.

IMPROVEMENT IN LUBRICATORS.

Specification forming part of Letters Patent No. 41,335, dated January 19, 1864.

To all whom it may concern:

Be it known that I, DAVID M. WESTON, a resident of Boston, in the county of Suffolk and State of Massachusetts, have invented a new and useful Mechanism for Lubricating the Journal of an Upright Shaft; and I do hereby declare the same to be fully described in the following specification, and represented in the accompanying drawings, of which—

Figure 1 denotes a front elevation, and Fig. 2 a vertical section, of an upright shaft with my invention applied to it.

In the drawings, A denotes the shaft whose journal *a* extends through and is supported by a bearing, *b*, suitably supported. A stationary cup, B, is fixed on the top of the bearing and encompasses the shaft and opens into the bearing.

Below the bearing *b* there is another cup or vessel, C, cylindrical in form and having an annular flange, *c*, projecting inward from the upper part of its periphery. A pipe, D, leading out of the cup C and upward is bent over at or near its upper end so as to discharge into the cup B, that part of the pipe which is

within the cup being curved around in the arc of a circle.

When there may be oil in the cup C, and such cup may be in rapid revolution with the shaft A, and in a direction toward the lower end of the pipe D, the centrifugal force generated in the oil will cause it to be thrown against the inner periphery of the vessel C, and from thence to flow upward through the pipe D and out of its upper end and into the cup B. From the said cup B the oil will pass into and through the bearing *b* and back into the cup C, from which it will be again forced up the pipe D and into the cup B. Thus the bearing, while the shaft may be in revolution, will continue to be lubricated with oil.

What I claim as my invention is—

The centrifugal oiling apparatus, composed of the cups B and C, and the pipe D, arranged with respect to the shaft A and its bearing *b*, substantially in the manner and so as to operate as described.

Witnesses:

D. M. WESTON.
